UNITED STATES PATENT OFFICE.

ALBERT E. STEWART, OF FRANKLIN, NEW HAMPSHIRE, ASSIGNOR TO ACME KNITTING MACHINE & NEEDLE COMPANY, A CORPORATION OF NEW HAMPSHIRE.

CAM-CYLINDER FOR KNITTING-MACHINES.

1,181,619.

Specification of Letters Patent. Patented Mar. 9, 1915.

Application filed August 29, 1913. Serial No. 787,283.

To all whom it may concern:

Be it known that I, ALBERT E. STEWART, a citizen of the United States, residing at Franklin, in the county of Merrimack and State of New Hampshire, have invented certain new and useful Improvements in Cam-Cylinders for Knitting-Machines, of which the following is a specification, reference being had to the accompanying drawings, forming part thereof.

This invention has reference to improvements in cam cylinders for knitting machines and particularly to the stitch cams of said cylinders and parts related to said stitch cams whereby the needles are guided.

One object of this invention is to so construct a cam cylinder for a knitting machine that the needles may be leveled, that the butts of the needles may pass the stitch cam without being acted upon thereby.

Another object of the invention is to improve the construction of cam cylinders for knitting machines.

The invention consists in a cam cylinder for a knitting machine having a stitch cam the leads of which are formed of movable members whereby said leads may be moved out of the path of the needle butts.

The invention also consists in the means carrying the lead or guide members of the stitch cam.

The invention also consists in such other novel features of construction and combination of parts as shall hereinafter be more fully described and pointed out in the claims.

Figure 1, represents a vertical sectional view of the cam cylinder of a knitting machine as taken on line 1—1 Fig. 2, illustrating this invention. Fig. 2, represents a plan view of portions of a cam cylinder for a knitting machine having my improvement but in other respects of any well known construction.

Similar characters of reference designate corresponding parts throughout.

In the operation of a knitting machine it is sometimes desirable to level the needles, that is to permit the movement of the butts of the needles in their circular path without vertical movement of the needles, as, for instance, in transferring from the knitting of the leg of a stocking to the top thereof. In carrying my invention into practice I accomplish this leveling of the needles by dividing both of the stitch cams in parts of which

the lower parts or members are fixed while the upper parts or guide members, together with the top center cam are so mounted that said guide members of the stitch cams and the top center cam can be simultaneously retracted out of the path of the needle butts whereby said needle butts may, in the relative rotary movement of the cam cylinder and the needles, pass the stitch cams without being guided vertically thereby.

As shown in the drawings 5 indicates the cam cylinder of any usual and well known construction to which my improvement is applied. At the inner wall of said cylinder are secured the raised stitch cams 6 and 7 having the bevel return ends 8 and 9 respectively which with the inclined edges 10 and 11 of the bottom center cam 12 form channels 13 and 14 leading to the inclined edges 15 and 16 of the cams 17 and 18 which form part of the usual cam ledge. The stitch cam lead or guide members 19 and 20 are separate from and fit the upper end portions of the stitch cams 6 and 7 and have the inclined edges 21, 22 and 23, 24, respectively and said lead or guide members 19 and 20 are mounted on the slide block 25 which is slidable radially relative to the cam cylinder in the guide box 26 formed in part with the wall 27 of the cam cylinder 5, and on this block 25 is also mounted the top center cam 28 positioned at a point intermediate the ends of stitch cam members 19 and 20 and extending above said cam members 19 and 20. Said block 25 is pressed inward by the spring 29 located between the block 25 and a fixed part of the bracket arm 30 which latter extends upward from the cam cylinder and integral with the guide box 26. This box 26 has in its upper wall a slot through which extends pin 31 fixed at its inner end to a member of the slide block 25 and having its outer end engaged by the thumb lever 32 pivotally mounted on the stud 33 secured in said guide box 26.

In the ordinary operation of the machine the butts of the needles will ride on the upper edges of the stitch cams 6 or 7, as the case may be, depending on the direction of relative rotary movement of the cam cylinder and the series of needles. When the butts of the needles meet the edge 21 of cam member 19 or the edge 24 of cam member 20 said needle butts will be guided upward in the direction of the top center cam 28 and,

after leaving cam member 19 or 20 will be guided downward and will then pass through one of the channels 13 or 14 to one of the channels between said stitch cam 6 or 7 and its related cam member 17 or 18.

When, now, it is desired to avoid the operation of the needles, last above described, manual pressure is applied to the free end of lever 32 to move said lever in a direction 10 to slidably retract block 25 and the parts attached thereto from its normal position so that the stitch cam members 19, 20 and the top center cam 28 are moved away, to one side, of the path of the needle butts at 15 this portion of the cam cylinder so that said needle butts in their riding movement are free to pass along the whole length of the needle leveling upper edge of stitch cam 6 or 7, then to the upper edge of the 20 bottom center cam 12 and from thence to the similar edge of the stitch cam 6 or 7 as the case may be, depending, as above stated, on the direction in which the needles or the cam cylinder is moving. When the operation of 25 leveling the needles is completed lever 32 is released and spring 29 acts to move block 25 and its cams back to normal position.

It is, of course, evident that this improvement may be applied to any cam cylinder of well known construction whether said cylinder is stationary or rotary but I prefer to make use of the same on a cam cylinder of the stationary type or construction and in combination with a rotary needle cylinder.

Having thus described my invention I claim as new and desire to secure by Letters Patent.

1. A cam cylinder for knitting machines comprising a cylindrical wall, a pair of stitch cams each consisting of upper and lower members of which the lower members are fixed to said wall and have upper needle leveling edges, a block slidably mounted to move radially between said fixed members of said stitch cams, said upper stitch cam members fixed to said block and having their lower edges in slidable contact with the needle leveling edges of said lower stitch cam members, and a top center cam mounted on said block.

2. A cam cylinder for knitting machines comprising a cylindrical wall, a pair of needle leveling stitch cam members fixed thereto and spaced apart, a bottom center cam fixed to said wall and having its upper edge in alignment with the needle leveling members of said stitch cams, a movable carrier above said bottom center cam, and a top center cam and a pair of stitch cam members mounted on said carrier, said latter pair of stitch cam members adapted in a position of said carrier to cooperate with said fixed stitch cam members.

ALBERT E. STEWART.
